PULL TOY

Andrew N. Giardina, Leetsdale, Pa.

Filed Mar. 28, 1960, Ser. No. 59,896

Term of patent 14 years

(Cl. D34—15)

Fig 2

FIG. 1 is a front perspective view of a pull toy showing my new design; and

FIG. 2 is a rear perspective view thereof.

I claim:

The ornamental design for a pull toy, substantially as shown.
